CLAIM

The ornamental design for a videotelephony device, as shown and described.

DESCRIPTION

FIG. 1 is a front elevation view of a videotelephony device showing my new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof; and,

FIG. 7 is a front perspective view thereof.

The broken lines in the drawings illustrate portions of the videotelephony device that form no part of the claimed design.

1 Claim, 4 Drawing Sheets
